Filed Jan. 26, 1962, Ser. No. 68,534

Term of patent 14 years

(Cl. D33—19)

FIG. 1.

FIG. 2.

The dominant features of the design reside in the portions of the drawings shown in full lines. The top and back of the cabinet are plain and unornamented.

The dotted lines indicating a wall in FIGURE 2 are for illustrative purposes only.

I claim:

The ornamental design for wall-mounted cabinet, as shown and described.
